UNITED STATES PATENT OFFICE.

ADDISON HULL, OF BROOKLYN, NEW YORK.

IMPROVEMENT IN GUIDES FOR SEWING-MACHINES.

Specification forming part of Letters Patent No. 16,586, dated February 10, 1857.

To all whom it may concern:

Be it known that I, ADDISON HULL, of the city of Brooklyn, in the county of Kings and State of New York, have invented a new and useful Improvement in Guides for Sewing-Machines; and I do hereby declare that the following is a full, clear, and exact description of the same, reference being had to the accompanying drawings, forming a part of this specification, in which—

Figure 1 is a back view of the foot-piece used in a sewing-machine to confine the cloth to the table having my improved guide attached. Fig. 2 is a plan of the same. Fig. 3 is a vertical section taken in the line *x x* of Fig. 2.

Similar letters of reference indicate corresponding parts in the several figures.

This invention consists in a novel mode of applying a guide in connection with the foot-piece, or the equivalent thereof, which confines the cloth to the table, which admits of its being adjusted readily at any suitable distance from the needle and renders it self-adjusting to various thicknesses of cloth or other material under operation.

To enable others to make and use my invention, I will proceed to describe its construction and operation.

A is a foot-piece, resembling that in common use in sewing-machines, attached to a leg, *B*.

C is a small plate fitted to slide through the foot-piece parallel with the face of the cloth or material under operation in a direction transverse to the feed movement and line of sewing or stitching, said plate containing a narrow slot, *a*, running in a direction parallel to its sliding movement to allow it to pass the needle *b*, which works through the said slot, as illustrated in Fig. 2, where the needle is shown in section.

c is the guide-plate, consisting of a narrow plate of metal arranged perpendicularly to the sliding plate *C*, and attached to the end of the said sliding plate *C*, by being provided with a small slot, *d*, which is arranged perpendicularly to the face of the cloth, and which receives a square pin or stud, *e*, formed on the end of the said sliding plate *C*, said pin or stud being furnished with a head on the outer side of the guide-plate to confine it to the sliding plate *C*. The slot *d* allows the foot-piece

to rise and fall to accommodate itself to the sewing of different thicknesses of material independently of the guide-plate, and whatever the thickness of the cloth it allows the lower edge of the guide-plate to rest upon the table when desired, or upon a portion of the material of different thickness to that upon which the foot-piece *A* presses, so that a portion of the guide-plate hanging below the plane of the face of the foot-piece may serve as the means of guiding the margin or other edge of the material, as is illustrated in Figs. 1 and 3, where the cloth is shown in section in red color, and also in Fig. 2, where the margin of the cloth is shown by a red line fitted with a dovetail to slide endwise into the small foot-piece *E** at the lower end of a rod, *E*, which works perpendicularly to the face of the cloth in a spring-box, *F*, that is attached rigidly to the leg *B* of the foot-piece *A* by an arm, *G*, which stands parallel with the face of the material, but transversely to the line of sewing, and consequently parallel with the sliding plate *C*. The spring *i* within the box *F* tends to force the guide-plate down below the face of the foot-piece *A*, so as to make a lateral bearing for the edge of the cloth to guide the same. The force of the spring may be graduated by a nut, *j*, acting on a screw on the top of the rod *E*, above the spring-box, and the same nut serves to lift the guide-plate entirely above the plane of the face of the foot-piece *A*, if at any time it be desired not to use the guide. The arm *G* is fitted to slide through the leg *B*, so as to allow the guide-plate to be set nearer to or farther from the needle to sew or stitch nearer to or farther from the edge of the cloth, and a set-screw, *f*, is employed to secure the arm in the required position. Instead of fitting the arm *G* to the leg *B* to attach the spring-box thereto, the said arm may be fitted in the same way to the stationary arm or stand of the sewing-machine. The rod *E* is prevented turning in the spring-box *F* by a feather or pin, *g*, on one side of the said rod, fitting to slide in a slot in one side of the spring-box, and thus the guide-plate is kept in sufficiently-rigid condition laterally. The guide-plate is kept from drawing longitudinally from the foot-piece *E** of the rod *E* by the sliding plate *C*. The reason for fitting the guide-plate into the foot-piece *E* so as to be movable, instead of securing it permanently thereto, is to enable

the straight guide shown to be changed for a curved one, or for a mere point for guiding curved seams, or for one of any desirable character for any purpose—as, for instance, a guide with a groove in its lower edge, to guide by the cord in stitching a corded edge. Whatever the form of the guide-plate it is confined with sufficient rigidity in a lateral and also longitudinal direction by its connection with the sliding plate C and the rod E, and yet is adjustable and changeable without interfering with the operation of the needle or any other part of the machine.

The slotted sliding plate C is an important feature, as it serves not only to prevent the guide-plate drawing longitudinally out of the foot-piece E*, but also serves to give it stability laterally.

I do not claim, generally, the attachment of

a guide to the foot-piece which presses on the cloth during the sewing operation; but

What I claim as my invention, and desire to secure by Letters Patent, is—

The attachment of the guide-plate c to a spring-bar, E, or its equivalent, which operates independently of the foot-piece A, thus holds the cloth during the sewing operation, and is adjustable laterally to the same, and the connection of the same by a vertically-slotted connection, d e, with a slotted sliding plate, C, working through the foot-piece A, substantially as described, whereby the guide-plate is made adjustable and changeable, as herein set forth.

A. HULL.
